UNITED STATES PATENT OFFICE.

ALEXANDER F. HUMPHREY AND RAYMOND C. MICHAELS, OF PITTSBURGH, PENNSYLVANIA, ASSIGNORS OF ONE-FIFTH TO WILLIAM L. SWARTZ, OF PITTSBURGH, PENNSYLVANIA.

FLUSH-TANK VALVE.

1,272,957.

Specification of Letters Patent. Patented July 16, 1918.

Application filed April 5, 1917. Serial No. 160,024.

To all whom it may concern:

Be it known that we, ALEXANDER F. HUMPHREY and RAYMOND C. MICHAELS, citizens of the United States, residing at Pittsburgh, in the county of Allegheny and State of Pennsylvania, have invented certain new and useful Improvements in Flush-Tank Valves, of which the following is a specification.

10 This invention relates to certain new and useful improvements in flush tank valves.

The primary object of the invention is the provision of a valve for flush tanks, the same being adapted for automatic operation 15 during the rise and fall of the water, means being arranged for equalizing the water pressure upon the valve whereby the latter is easily opened and closed and the so-called "water hammer" is eliminated.

20 A further object of the device is to provide a float controlled valve adapted for positioning in the corner or at any other point within a tank, the structure being formed of few parts readily separable and 25 not liable to get out of order while the valve is easily actuated upon a change in the level of the water within the tank.

With these general objects in view and others that will appear as the nature of the 30 invention is better understood, the same consists in the novel combination and arrangement of parts hereinafter fully described, illustrated in the accompanying drawings and then claimed.

35 In the drawing forming a part of this application and in which like designating characters refer to corresponding parts throughout the several views,

Figure 1 is a side elevation of the device.

40 Fig. 2 is a top plan view thereof.

Fig. 3 is a vertical sectional view taken upon line III—III of Fig. 2.

Fig. 4 is a vertical central longitudinal sectional view of the device.

45 Fig. 5 is a central vertical sectional view of a slightly modified form of the invention operatively mounted upon the floor of a tank, and,

Fig. 6 is a top plan view thereof.

50 Referring more in detail to the drawing, it will be understood that the device being designed for controlling the in-flow of water to a tank, the device is positioned therein, the form illustrated in Fig. 1 being serv-55 iceable when it is found desirable to posi-

tion the valve in compact arrangement within one corner portion of the tank while the structure shown in Fig. 5 is identical in its operation as well as its essential elements of construction being readily positioned at 60 any desired point within the tank.

Referring more in detail to the form of invention illustrated in Fig. 1, the same consists of a tubular casing 10 having an axial bore 11 extending therethrough, a bottom 65 extension 12 being carried by the casing for attachment in an upright position to the bottom of the tank, not shown. The lower portion 13 of the bore 11 constitutes the water inlet for the casing while the upper 70 portion 14 thereof is of a slightly enlarged diameter and forms a chamber within which a cylindrical valve 15 is adapted for longitudinal reciprocation.

The lower end of the chamber 14 is enlarged as at 16 while the valve seat 17 is 75 removably threaded into the bottom thereof having an opening 18 therethrough communicating with the inlet bore 13, a plurality of outlet ports 19 being provided downwardly inclined leading from the enlarged chamber 16 while a suitable outlet spout 20 also leads from the said enlarged chamber.

A packing or washer 21 is preferably secured to the lower end of the valve 15 by 85 means of a screw 22 for engaging the valve seat 17 while a packing 23 is secured upon the upper end of the valve for giving the valve a tight fitting connection within the chamber 14, it being noted that the valve 90 15 has an upward reduced cylindrical stem 24 for receiving the washer 25 overlying the packing 23 as well as a suitable lock nut 26. A cap 27 is threaded upon the upper end of the casing 10 for limiting the upward 95 movement of the valve, the central socket 28 thereof affording a guide for the valve stem 24.

A longitudinal enlargement 29 is provided for the casing 10 for the accommodation of 100 a by-pass passage 30 connecting the water inlet 13 with the valve chamber 14 at a point above the valve 15 while the casing 10 is also preferably bulged annularly as at 31 for accommodating the chamber portion 16. 105

A float arm 32 is pivoted between lugs 33 projecting from the casing 10 by means of a pin 34 and extends through a slot 35 in the side of the casing 10 and having a foot 36 at its inner end freely arranged within the 110

side notch 37 of the valve 15, it being understood that a float, not shown, of any desired construction is attached to the opposite free end of the arm 32. The usual form of refill 5 pipe or siphon tube 38 is carried in an upright position by a boss 39 of the casing 10 communicating with the chamber 16 by a port 40.

The operation of the device will be apparent as the float arm 32 will be maintained by the float in the position illustrated in Figs. 1 and 4 of the drawing under normal conditions with the packing 21 of the valve 15 in seating engagement with the valve seat 17. Upon a lowering of the water within the tank and the consequent dropping of the float and outer end of the float arm 32, the foot 36 elevates the valve 15 admitting water through the inlet 13 into the chamber 16 for passing outwardly through the spout 20 into the flushing tank, a comparatively small amount of water also passing through the by-pass 30 into the chamber 14 above the valve 15 thereby equalizing the water pressure at both ends of the valve. The main outlet for the water is through the spout 20 although the ports 19 allow some of the water to pass therethrough, increasing the out-flow, decreasing the outward pressure of the water and lessening the amount of noise incident thereto. A small quantity of water passes from the chamber 16 through the pipe 38 for refilling the bowl after the flushing operation and forming the water seal as usually provided in such structures.

The form of the invention shown in Figs. 5 and 6 of the drawing embodies all of the same elements heretofore described and it is believed unnecessary to repeat such description, it being noted that the only difference is in closing the bottom of the valve casing 10' and forming a branching connection with the valve chamber 14' above the valve 15' and the inlet 13' below the valve seat 17', the same providing a relatively small passage 30' leading to a point above the valve and an enlarged passage 41 below the same each communicating with the rearwardly extending inlet end 12' of the casing 10'. A

water conduit or supply pipe 42 is fixed 50 through the bottom 43 of the flushing tank with the valve attached thereto by means of the rear end 12' thereof. It will be seen that the operation of this form of the device is identical with that heretofore described, a 55 float arm 32 being arranged having a forked inner end 36' freely engaging in the side notches 37' of the said valve 15'.

A valve is arranged that is easy and inexpensive to manufacture having readily 60 changeable parts and being easily and noiselessly operated within a flushing tank by the float mechanism thereof.

What we claim as new is:—

1. A device of the class described comprising a casing having an axial chamber therein provided with an enlarged lower portion having a plurality of relatively small side outlet ports, a valve seat arranged at the bottom of said enlarged portion, an outlet spout 70 for said enlarged portion, and a float controlled reciprocating valve within said chamber having one end adapted for engagement with said seat when the valve is closed, said casing having a water inlet opening communicating with said chamber at points above and below said valve. 75

2. A device of the class described comprising a casing having an axial chamber therein provided with an enlarged lower portion 80 having a plurality of relatively small side outlet ports, a valve seat arranged at the bottom of said enlarged portion, an outlet spout for said enlarged portion, a float controlled reciprocating valve within said chamber having one end adapted for engagement 85 with said seat when the valve is closed and provided with a reduced guide stem on the other end thereof having a packing secured thereon, and a guide and stop cap for said 90 stem secured to the upper end of the casing, said casing having a water inlet opening communicating with said chamber at points above and below said valve.

In testimony whereof we affix our signatures.

ALEXANDER F. HUMPHREY.
RAYMOND C. MICHAELS.
